CENTRIFUGAL MILL HAMMER WITH RENEWABLE WEARING TIP

Frank J. Loufek, Cedar Rapids, Iowa

Application July 23, 1947, Serial No. 762,983

2 Claims. (Cl. 241—197)

1

This invention relates to hammer mills for breaking stone and the like hard, fracturable materials, and more particularly to improved renewable hammers therefor. Hammer mills for stone and similar materials, as usually constructed, have a closed housing equipped with a chute for introducing the material to be broken. The bottom portion of the housing, or at least a part of it, is composed of apertured grids which are usually of exceedingly hard and tough steel, such as cast manganese steel. The grid surface is cylindrical and through the housing, and axially of the cylindrical grid surface there is a rotatably mounted shaft which, in the usual construction of mill, carries spaced discs of heavy construction that are apertured to provide a mounting for through pivot pins on which a plurality of swinging hammers are mounted.

In early hammer mills it was usual practice to make the swinging hammers of one unitary casting, one end being apertured so as to journal and hence swing on the pivot pin when mounted in place; the free end of the hammer being, in co-operation with the cylindrical grid, the stone breaking surface.

Both the grids and the hammers wear during service, the normal life being only a matter of hours before "turning" of the hammers to expose a new striking surface, or replacement is necessary, for the operating conditions are extreme. For removal and replacement the machine is usually constructed so that the hammer mounting pins could be driven out through access places in the mill housing and through holes in the shaft flywheel. Replacement or "turning" of hammers is not an easy task, for the parts tend to "lime up," that is to say, during service the interstices in bearing mounting etc. become packed with finely ground stone. Consequently, many hours of hard work are needed to drive out the pins and replace or "turn" the hammers. "Replacing or turning the hammers" has, therefore, been very expensive, not only in labor and parts but also in out-of-service time of the mill.

An attempt has heretofore been made to reduce these costs by providing a hammer with a two-part body and a removable tip. While this type hammer has achieved a considerable acceptance its use has been attended by considerable disadvantages. To disconnect the hammer tip from the two-part body portion of the hammer, it is first necessary to remove the latter from the mill so as to allow the two parts of the body portion to be separated. Consequently, it is still necessary, when using this type hammer assembly, to drive out the hammer mounting pins through the mill housing and flywheel each time the hammers need to be "turned" to expose a new striking face or for "renewal." This constitutes a continuing service cost which is not

2

eliminated. Furthermore, when the hammer assemblies are removed, it is difficult to remove the tips because, by the nature of the connection between tip and two-part body portion, there is considerable interstitial space which becomes "limed up," i. e. filled with finely powdered stone, which packs hard and frequently defies removal. This is also a continuing service cost.

Furthermore, the nature of the assembly of previously patented, removable tip hammers has necessitated removing the hammer mounting pins each time the tip is turned or the hammer replaced.

It is an object of the present invention to provide an improved renewable tip hammer for hammer mills and more particularly to provide an improved renewable tip hammer wherein the task of turning the tips or renewing the hammer tips can be accomplished conveniently without removing the hammer mounting pins or body portion of the hammers from the mill, and which is capable of being manufactured and serviced at minimum costs.

Other objects of the invention include the provision of a hammer assembly having only two principal parts held together by an easily removable through bolt, and in which the two principal parts may be separated by simple transverse sliding movement without separating the hammer assembly from the mill.

Other and further objects of the invention are those inherent in the apparatus herein illustrated, described and claimed.

The invention is illustrated in the drawings in which

Figure 1 is a transverse section through a typical hammer mill wherein the hammers are made in accordance with the present invention;

Figures 2 through 5 illustrate one style of improved hammer of the present invention, hereinafter referred to as type A. Figure 2 is a side elevational view; Fig. 3 is a vertical section taken in the direction of and along line 3—3 of Figure 2; Figure 4 is a perspective view with the parts separated so as to illustrate the manner of assembly; and Figure 5 is a detail of the right-hand side plate of the assembly, as shown in Figure 3;

Figures 6 through 8 illustrate another style of improved hammer for hammer mills of the present invention hereinafter referred to as type B. Figure 6 is a side elevational view; Figure 7 is a vertical section along the line and in the direction of arrows 7—7 of Figure 6; and Figure 8 is a perspective view with the parts separated so as to illustrate the manner of assembly;

Figures 9 through 11 illustrate still another style of improved hammer for hammer mills of the present invention, hereinafter referred to as type C. Figure 9 is a side elevational view; Fig-

ure 10 is a vertical section along the line and in the direction of arrows 10—10 of Figure 9; and Figure 11 is a perspective view with the parts separated so as to illustrate the manner of assembly.

Figures 12 through 17 are a series of views showing the manner in which the tips are reversed and the hammers set down through successive steps so as to maintain grinding efficiency and utilize all of the hammer tip material.

Throughout the drawings, corresponding numerals refer to the same parts.

Referring to the drawings, particularly Figure 1, there is illustrated a hammer mill particularly designed for crushing hard materials, such as stone, cement, rock, and the like. Figure 1 is representative of hammer mills of this type and consists of a sub-frame 10 having an upper surface internal and external flange 11 on which the crusher assembly is mounted. The crusher consists of a heavy cast or welded structure having a base plate 12 and upwardly extending walls 14 and 15. Between the base plate 12 at the left side and the internal bracing frame member 16 there is a pocket 17 into which tramp iron is tossed during the operation of the mill, and this is covered by a clean-out door 18. The sub-frame 10 also serves as a support for a cylindrical milling grid generally designated 20 which is usually cast in sections and is of exceedingly hard and tough material, such as manganese steel. The grid has a cylindrical inner surface 21 which is apertured so as to form a screen or grid through which the pulverized material 22 falls during the operation of the mill. The grid 20 may be composed of several parts suitably supported on the sub-frame 10. The exact construction of the grid forms no part of the present invention. Within the wall portion 14 there is, in the illustrated mill, a plate 24 which is hinged at 25 and arranged for adjustable movement by virtue of the adjusting bolt 26. The hinge plate 24 is faced with a cast, hard, tough plate 27 having an irregular grinding surface 33. The upper portion of the mill is closed as at 28 and 29. The frame members 15, 16 and 29 serve to support a minute chute shown under the bracket 30 through which the large size material which is to be pulverized is fed downwardly in the direction of the arrow 31.

The exact structure of the mill is varied considerably, depending upon the particular design features stressed by various manufacturers, but all the mills of this character have in common the idea of using a reticulated cylindrical grinding surface, here represented by the grid 20, and a rotatable hammer assembly, here generally designated 37. The rotatable hammer assembly is mounted upon the shaft 32 which is suitably journaled in the end plates of the mill and driven from an adequate power source. Customarily, the shaft 32 has on it a heavy flywheel (or flywheels) exteriorly of the frame at one (or both) of the ends of the mill to which the power drive is applied in any suitable manner. Within the mill, the shaft 32 is provided with a plurality of spaced discs 34 which are keyed onto the shaft at 35. The discs are provided with a plurality of spaced apertures, viz. 36A, 36B and 36C usually on radii which are spaced at equal angular intervals around the discs. In some mills the distance from the center of the shaft 32 to the center of the holes 36A, 36B and 36C is varied slightly so as to vary the position at which the hammers are pivoted with reference to the main shaft 32, while in other mills all of the holes 36A, 36B and 36C

are at equal distance from the center of the shaft, the plurality of holes being provided in such instances only to allow shifting of the hammer anchor pins 38 when wear occurs. In the illustrated embodiment the distance of the holes from the center of the shaft is varied slightly. Thus, holes 36A have the shortest radius from the center of shaft 32 and are used when the hammers are new and of maximum length, Figures 1 and 12-17. Holes 36B are at a medium radius and are used when the hammer tips begin to wear some, while holes 36C are set at the longest radius from shaft 32 and are used when the hammer tips are worn nearly to their limit of usefulness.

The holes 36A, 36B and 36C of the adjacent spaced parallel discs 34 are aligned from disc to disc so that the long anchoring pins 38 may be driven through all of the discs and when in place the pins 38 are thus parallel to the axis of the shaft 32. The spacing of the discs is sufficient to permit the pivot end of the hammers, generally designated A, B and C herein, to be placed between the discs. In Figure 1 the hammers shown are of type C, hereinafter more fully described. It is to be understood that in this specification the mill illustrated in Figure 1, per se, forms no part of the present invention and that the invention is in the particular type of hammer which is used in the mill.

Referring to Figures 2 through 4 there is illustrated one form of the improved removable tip hammer of the present invention. The hammer consists of a main body portion 40 which has a thickness T, Figure 3, sufficient that it occupies, except for a clearance, the space between successive discs 34 of the mill. The main body portion is provided with an aperture 41 of a size such that it will pivot neatly upon the pivot pins 38 of the mill when the hammer assembly is in place thereon.

Referring to Figure 2 the main body portion 40 of the hammer extends outwardly from the hole 41 and terminates in a dove tail portion generally designated 42, the dove tail portion being defined by the line 44 which extends transversely across the hammer to and then around the smoothly rounded curve portion 45 and thence outwardly to the smoothly rounded curve portion 46, thence again transversely along the line 47 and around the smoothly rounded curve portions 48 and 49 and thence outwardly along a transverse line 50 which is in the same plane as the line 44. The surface defined by the line 44—50 may thus be defined as generated by moving a line parallel to the axis of the pivot hole 41 (which is also parallel to the axis of pivot pin 38 and to the axis of rotation of the shaft 32) along the line 44—50 which defines the dove tail end of the main body portion.

The removable extremely hard and tough hammer tip portion generally designated 51 has a cast-in recess of the same shape as the dove tail on the portion 40 except that slight clearance is allowed in the dimensions so that the hammer tip 51 may be slid parallel to the axis of hole 41 for placement of the hammer tip on the main body portion 40 of the hammer and also for removal. The tongue portions 52 and 54 of the hammer tip 51 thus are seated within the smoothly rounded curve portion 45 and 49 of the main body part 40 of the hammer, and the hammer tip is therefore held firmly against outward movement in the direction of arrow 56 when the mill is in operation.

Movement of the hammer tip 51 parallel to

the axis of hole 41, which would permit the hammer tip to uncouple from the main body portion 40 of the hammer, is prevented during the operation of the mill by a pair of retaining plates 58 and 59 which are seated into recesses 60 and 61 in the side of the hammer assembly. It will be noted that each of the recesses 60 and 61 is formed in part in the main body portion 40 of the hammer and in part in the hammer tip 51.

The retaining plate 58 is cut away as indicated at 62 so as to provide a surface in which the head 64 of a bolt 65 is seated in a somewhat protected position. Similarly, plate 59, which is shown in Figure 5, is provided with a recess at 66 to receive the nut 68 into which the bolt 65 is screwed for clamping the plates 58 and 59 in place in assembled relation, as shown in Figure 3. Thus, in fitting the parts of the hammer assembly together the tip is first moved in a direction parallel to the axis of the hole 41 so as to bring the two tongues 52 and 54 into engagement with the dove tail end of the main body portion 40 of the hammer. Then the plates 58 and 59 are mounted in the recesses 60 and 61, respectively, and they are in turn held in place by the bolt 65 which is inserted through the aperture 69 of plate 58 which continues as the aperture 70 through the main body portion and thence continues as aperture 71 in plate 59, the bolt 65 being then turned up firmly into the nut 68 which is held from rotation due to the configuration of the recess 66 in the retaining plate 59. Above the aperture 69—70—71 there is a smaller aperture 73—74—75 formed in part in the plate 58, the main body portion 40 and the plate 59, respectively. This smaller aperture is located so that when the cotter pin 76 is inserted therethrough the enlarged loop head 77 of the cotter pin will lie against one of the flat surfaces of the head 64 of bolt 65 and thus prevent it from turning. The opposite end of the cotter pin is bent over, as indicated at 78, Figure 3.

Referring to Figures 6, 7 and 8 there is illustrated a slightly modified form of the invention, namely type B which is the same as type A of Figures 3 through 5 except that the hammer tip is provided with internal recesses 80 and 81 extending downwardly from the recesses 60 and 61 which, as explained with reference to type A, is formed in part in the main body portion 40 and the hammer head 51. The retaining plates 58 and 59 of type B, Figures 6-8, are likewise provided with downwardly extending portions 82 and 83, respectively, which fit into the recesses 80 and 81 when the plates are rotated from the dotted line positions shown in Figure 7 to the full line positions. The portions 82 and 83 which are the outward ends of the plates 58 and 59, respectively, when the hammer is working, are thus held in the recesses 80 and 81, respectively, and this makes for less possibility of displacement of the retaining plate during operation. The bolt 65, Figures 6-8, thus has only to hold the inner (upper) ends of the plates 58 and 59.

Referring to Figures 9-11 there is illustrated a further modified form of the invention, herein known as type C. In this modification of the invention the main body portion 90 of the hammer is, as before, provided with an aperture 91 through which the mounting pins 38 are inserted for attaching the hammer assembly to the rotor of the mill. The main body portion is likewise provided with a dove tail end shaped along the

line 94, 95, 96, 97, 98, 99, 100, but in this instance the dove tail end is not shortened in a transverse direction, but, on the contrary, is somewhat thicker than the dimension T1 at the mounting end of the hammer assembly, Figure 10, it being noted that the hammer body portion 90 in the direction parallel to the axis of hole 91 is formed with curved surfaces at 101 and 102 terminating in the surfaces 103 and 104 which are spaced 10 apart by the distance T2 (Figure 10) which is also the head width of the hammer. The hammer tip 105 has a side view shape the same as that shown for types A and B, being provided with a recess of dove tail shape at 106 corresponding to the dove tail end 94—100 of the main body portion 90 of the hammer. The assembly of the hammer tip 105 to the main body portion is, as with types A and B, accomplished by sliding the hammer parallel to the axis of hole 91 until the hammer tip is aligned, as shown in Figure 10. Across the end of the dove tail joint formed in the main body portion 90 and the hammer tip 105 and on each of the faces 103 and 104 of the hammer assembly, there are 20 provided recesses. Thus, recess 108 is provided in the face 103 and recess 109 in face 104. Each of these recesses overlaps the dove tail end of the main body portion 90 and the hammer tip and the recesses are of sufficient depth to receive 30 the head 110 and nut 111 of the retaining bolt 112 which passes through a hole 114 that is formed in the boundary of the dove tail portion 94—100 of the main body portion and the corresponding dove tail portion 106 of the hammer tip 105. Adjacent the hole 114 there is a smaller hole 115 through which the cotter pin 116 extends. When the cotter pin is in place and crimped over, the head 118 is held flat against one of the flat sides of head 110 of bolt 112 and thus prevents it from turning. Similarly, the crimped end 119 of the cotter pin prevents 40 the nut 111 from turning. If desired, the aperture 109 may be made smaller so as to fit the configuration of the nut 111 leaving only a small space in which the cotter pin 119 may be crimped down. When so formed the cotter pin need serve only to hold the head 110 of the bolt from turning rather than both the head and the nut thereof.

It may be noted that in each of the three styles of hammer assemblies previously described the hammer and hammer tip are symmetrical about a central plane passing lengthwise through the hammer assembly and through the axis of the pivot of the hammer. Being so constructed the hammer tip of any of the modifications may be reversed with respect to the hammer body without removing the latter so as to present a new breaking surface. This is illustrated in Figures 12 through 17 which also show the manner in which the hammer assembly may be set radially outward in successive steps so as to utilize all or most of the material in the hammer tip. In this group of figures the lines 36A, 36B and 36C represent the path of movement of the holes 36A, 36B and 36C of Figure 1. Thus, the line 36A which represents hole 36A of Figure 1, is the shortest radius while line 36B represents the medium radius and 36C represents the longest radius. In Figures 12 through 17 the particular style of hammer illustrated is that shown in Figures 9 through 11, but it is to be understood that Figures 12 through 17 are equally representative 70 of the manner of use of the style of hammer

assemblies shown in Figures 3 through 5 and 6 through 8.

When the hammer tip is new it has a rectangular configuration of its outer end, as shown in Figure 12. During initial use the hammer is mounted on its pivot pin which is then placed in hole 36A, thus rotating the hammer at the shortest radius (from the center of shaft 32). This is possible since at this time the hammer tip has its maximum dimension. As the hammer tip grinds material, its striking surface finally wears to the shape shown by the dotted line *a*—*b*, which is the first stage of wearing. The mill is then shut down and the hammer tip 105 is reversed to the position shown in Figure 13 which then brings the line *a*—*b* to the rear edge of the hammer away from the striking surface. At this change the hammer mounting pins remain in holes 36A. The mill is then again put into operation and the striking surface of the hammer tips then wears away until the tips assume the configuration shown by the line *c*—*d*—*a*. This is the second stage of wearing.

The mill is then again shut down and the pivot pins 38 are removed and the entire hammer assemblies and the pins 38 are set down to the medium radius hole at position 36B. This has the effect of bringing the entire hammer to a longer radius with reference to shaft 32 and brings the hammer tip closer to the grid 20. This position is shown in Figure 14. The mill is again put in service and the hammer tips during operation wear away to the dotted line *e*—*f* which is the third stage of wearing. The mill is then taken out of service, the bolts 112, holding the hammer tips in place, are removed and the hammer tips are reversed, which has the effect of positioning the hammer tips as shown in Figure 15. The mill is then again put in service and gradually wears the hammer tips to the dimension shown by the dotted line *g*—*h* which is the fourth stage of wearing, at which time the mill is again taken out of service and the pins 38 are removed and the hammers are set out to the longest radius hole 36C. This new positioning is illustrated in Figure 16. When the mill is again put in service the hammer tips again wear, this time to the dimension shown by the dotted line *i*—*j* which is the fifth stage of wearing, whereupon the mill is again shut down, the bolts 112 are removed and the hammer tips are reversed to the position shown in Figure 17 and upon again being put in service, the tip wears to the dimension shown by the dotted line *k*—*l*, which is regarded as the final stage of usefulness. The pins 38 and all the hammers are then removed, the bolts 112 are loosened from each of the hammers and each hammer is then provided with a new replaceable tip of full dimension, and the hammers are reassembled to the shortest radius hole 36A, as in Figure 12.

In Figures 12 through 17 the original dimensions of the hammer tips are shown in dotted lines for purposes of illustrating the amount of material which is worn away during service life of the hammer tip. It will be appreciated that by this manner of construction the hammer tip is given an exceedingly long, useful life and that the out-of-service time of the mill required for reversing or setting out the hammers is reduced to a minimum. It may be noted parenthetically that some operators reclaim the hammer tips by welding-on additional material by the electric

arc welding process, although this frequently gives bad results due to the fact that it introduces variations in the length and width of the hammer tips, thus upsetting proper operation of the mill.

As many apparently widely different embodiments of this invention may be made without departing from the spirit and scope thereof, it is to be understood that I do not limit myself to the specific embodiments herein except as defined by the appended claims.

What I claim is:

1. A hammer comprising a main body portion formed with an opening adjacent one end thereof, a dove tail portion formed at the opposite end of the main body portion, a hammer tip portion formed with a pair of forwardly facing tongues with curved ends, said tongues received in mating engagement with said dove tail portion, rectangular depressions formed in either side of the body portion and the hammer tip portion and overlapping the tongues and dove tail portion, plate like retaining means fitting the depressions in the body portion and the hammer tip portion, fastening means passing through aligned holes in the retaining plates and the body portion, and the portion of the retaining plate adjacent the fastening means being of lesser thickness than the remaining portion for protecting the ends of the fastening means from wear.

2. A hammer comprising a main body portion formed with an opening adjacent one end thereof, a dove tail portion formed at the opposite end of the main body portion, a hammer tip portion formed with a pair of forwardly facing tongues with curved ends, said tongues received in mating engagement with said dove tail portion, rectangular depressions formed in either side of the body portion and the hammer tip portion and overlapping the tongues and dove tail portion, plate like retaining means fitting the depressions in the body portion and the hammer tip portion, fastening means passing through aligned holes in the retaining plates and the body portion, and the portion of the retaining plate adjacent the fastening means being of lesser thickness than the remaining portion for protecting the ends of the fastening means from wear, said hammer tip portion formed with internal recesses at either side thereof adjacent the rectangular depressions, and said retaining plates formed with downwardly extending portions receivable within said internal recesses.

FRANK J. LOUFEK.
